TRACK RELEASE MECHANISM

Emil F. Norelius, Springfield, Ill., assignor to
Allis-Chalmers Manufacturing Company, Milwaukee, Wis., a corporation of Delaware

Application July 26, 1940, Serial No. 347,572

28 Claims.

(CL. 305—9)

The invention relates to endless track vehicles, and it is concerned more specifically with an improved track release mechanism for preventing damage to an endless flexible track belt and its supporting structure in case a rock or other solid obstruction should become lodged between the track belt and one of its supporting wheels.

In order to permit a rock or other solid obstruction to pass between the track belt and its supporting structure, it has heretofore been common practice to mount one of the track supporting wheels on a reciprocable or swingable bearing and to urge the bearing by means of a resilient mechanism into a normal operating position, that is, into a position in which the movably mounted track supporting wheel, usually termed the "track idler," is spaced from the other track supporting wheel a proper distance to insure proper support of the track belt on both track supporting wheels during normal operation of the self-laying track unit. The resilient mechanism operates to resist movement of the track idler and its bearing from said normal operating position into a track releasing position, and to keep the track idler and its bearing in said normal operating position, as long as the track tension remains normal, but when the track tension becomes excessive due to a solid obstruction being drawn between the track belt and its supporting structure, the resilient mechanism yields and permits the bearing to move in track releasing direction. After the obstruction has been cleared, the bearing is restored to its normal operating position by the resilient mechanism.

It is an object of the invention to provide a self-laying track unit having an improved track release mechanism of the mentioned character, that is, a self-laying track unit in which one of the supporting wheels for the track belt is mounted on a frame for movement from a normal operating position into a track releasing position, and in which such movement of the supporting wheel is controlled in an improved manner by means of a resilient mechanism.

In order to resist track releasing movement of the bearing various types of spring operated mechanisms have heretofore been suggested in which one or more initially compressed coil springs exert the necessary pressure for maintaining the track idler in normal position. Movement of the bearing in track releasing direction causes further compression of the spring or springs, and if the rate of movement of the bearing equals the rate of compression of the spring, as has heretofore been usual in mechanisms of this type, the track tension increases in proportion to the track releasing travel of the bearing. As a result, the strain upon the track belt

and its support steadily increases as the bearing moves in track releasing direction, and as long as an obstruction remains lodged between the track belt and its support such strain is greater than that resulting from the normal track tension.

It is another object of the invention to provide an improved track release mechanism which will resist a certain permissible track tension in excess of the normal track tension while the releasable track supporting wheel and its bearings are located at or near a normal operating position, but which mechanism will permit the track supporting wheel and its bearing to recede from said normal operating position, or from a position in proximity thereto, a substantial distance in a track releasing direction after the track tension has exceeded the mentioned permissible amount, the resistance opposing such receding movement of the wheel and bearing being not greater than the initial resistance against which the excessive track tension is permitted to build up.

More specifically, it is an object of the invention to provide an improved track release mechanism of the mentioned character in which the releasable track supporting wheel and its bearing are subject to a relatively high initial resistance against movement in track releasing direction but are less forcibly opposed once said initial resistance has been overcome and track releasing movement of the bearing has started. Preferably, the resistance is made to decrease during the first part of the total travel allowed for track releasing movement of the bearing. Such a construction of the mechanism is desirable because, if an obstruction becomes lodged between the track belt and its supporting structure, the track tension rises above normal only for a relatively short time, that is, until the obstruction has been drawn in between the track belt and its supporting structure far enough to move the bearing a relatively short distance in track releasing direction.

A further object of the invention is to provide a spring operated mechanism for producing the mentioned relatively high initial resistance against movement of the releasable track supporting wheel from a normal operating position into a track releasing position, and for opposing said movement of the track supporting wheel less forcibly after said initial resistance has been overcome and the wheel has been moved a relatively short distance in track releasing direction.

A further object of the invention is to provide an improved track release mechanism which is simple and compact in construction, efficient in operation, and which may be manufactured at relatively low costs.

These and other objects and advantages of the invention will be apparent from the follow-

ing description of a preferred embodiment of the invention. Referring to the drawings accompanying and forming part of this specification, and in which like reference characters designate the same or similar parts in the several views:

Fig. 1 is a side view of a crawler tractor embodying the invention;

Fig. 2 is a top view of the tractor shown in Fig. 1, the track belt at the left side of the tractor being omitted to expose the track release mechanism of the self-laying track unit at the left side of the tractor. A similar track release mechanism, not shown, is incorporated in the self-laying track unit at the right side of the tractor;

Fig. 3 is an enlarged sectional view of the mechanism for controlling movement of the track idler shown in Figs. 1 and 2, the view being taken in a plane at right angles to the axis of the idler and showing the mechanism in its normal position;

Fig. 4 is a view similar to Fig. 3, but showing the mechanism in its extreme track releasing position;

Fig. 5 is an enlarged section on line V—V of Fig. 1, showing the front idler mounting;

Fig. 6 is a side view of a bearing shown in Fig. 5;

Fig. 7 is a top view of the bearing shown in Fig. 6;

Fig. 8 is a section on line VIII—VIII of Fig. 1, showing a bearing support within the housing of the track release mechanism; and

Fig. 9 is a section on line IX—IX of Fig. 3, showing the pivot mounting of a link within the housing of the track release mechanism.

The tractor shown in Figs. 1 and 2 comprises a main body shown in outline and generally indicated by the reference character 1, and a pair of self-laying track units including track belts 2 and 3 at opposite sides of the main body. A sprocket wheel 4 for driving the track belt 2 at the left side of the tractor is mounted on the main body 1 in the usual manner for rotation about a transverse shaft 5 at the rear of the main body, and a similar sprocket wheel for driving the track belt 3 at the right side of the tractor is rotatably mounted on the main body coaxially with the sprocket wheel 4, as will be understood by those skilled in the art. The driving sprockets are drivingly connected with an engine at the forward end of the main body 1 by the usual master clutch, change-speed mechanism and steering clutches, which are conventional elements of the main body and do not form part of this invention.

The shaft 5 on which the sprocket wheel 4 is mounted has an outward extension, and journaled on said outward extension of the shaft 5 is a bearing 6 for connecting a track frame at the left side of the tractor to the rear of the main body. The track frame comprises an outer channel iron 8 secured at its rear end to the bearing 6, an inner channel iron 9 extending parallel to the outer channel iron 8, and an inverted top channel iron 10 (Fig. 8) connecting the inner and outer channel irons 8 and 9. The top channel iron 10 is of sufficiently short length to leave an unobstructed space between the forward ends of the inner and outer channel irons 8 and 9, for mounting of a front idler 12.

Referring to Fig. 5, it will be seen that the front idler 12 is rotatably mounted on a shaft 13 by means of two conical roller bearings 14 and 15, the inner races of the roller bearings

abutting against flanges 16 on the shaft and the outer races being engaged by bearing retainers 17 secured to the hub of the idler wheel 12. Press-fitted upon opposite ends of the shaft 13 are two brackets 18 and 19, and rotary seals 20 and 22 are interposed between the brackets and the bearing retainers to seal the interior space of the hub of the idler 12 containing the roller bearings 14 and 15. The bracket 18 has a base portion of substantial length and width overlying the top flange of the outer channel iron 8, and the bracket 19 has a similar base portion of substantial length and width overlying the top flange of the inner channel iron 9. A shoulder 23 extends downwardly from the bracket 18 adjacent to the inner side of the channel iron 8, and a shoulder 24 extends downwardly from the bracket 19 adjacent to the inner side of the channel iron 9 to retain the front idler assembly against displacement transversely of the track frame. The entire front idler assembly, including the idler wheel 12, shaft 13, and brackets 18 and 19, is slidable as a unit longitudinally of the track frame, the base portions of the brackets 18 and 19 having smooth horizontal bottom surfaces slidably bearing upon the smooth horizontal top surfaces of the upper flanges of the channel irons 8 and 9, respectively. A guide block 25 secured to the bracket 18 projects under the top flange of the channel iron 8, and another guide block 27 projects under the top flange of the channel iron 9 to keep the idler assembly and track frame together vertically. In addition to the shaft 13, the bracket 18 carries a guard 28 (Fig. 5) for the idler wheel 12, the guard being secured to the bracket 18 at forward and rearward shoulders 29 and 30 thereof, the forward shoulder 29 extending upwardly from the base of the bracket in front of a central barrel portion 32 which surrounds the shaft 13, and the rearward shoulder 30 extending upwardly from the base of the bracket in rear of the barrel portion 32, as shown in Figs. 6 and 7, in which figures the guard 28 has been omitted. Another idler guard 33 corresponding to the idler guard 28 (Fig. 5) is secured to the bracket 19 at forward and rearward shoulders 34 and 35 thereof corresponding to the forward and rearward shoulders 29 and 30 of the bracket 18.

A thrust transmitting yoke 37 extends rearwardly from the front idler assembly and has two legs at opposite sides, respectively, of the idler wheel 12, one of the legs being secured to the rearward shoulder 30 of the bracket 18 by means of two bolts 38, and the other leg of the yoke being similarly secured to the rearward shoulder 35 of the bracket 19. Formed integrally with the bridge portion of the yoke is a rearwardly extending sleeve which is split at 39 and has a horizontal threaded bore for the reception of an adjusting screw 40. The adjusting screw has a rearward polygonal shoulder 42 for turning it within the threaded bore of the yoke, and the sleeve portion of the yoke has a pair of lugs 45 through which extend two clamping bolts 43 for securing the screw 40 against turning in any adjusted position. A semi-spherical head 44 is formed on the screw 40, forwardly of the shoulder 42, for cooperation with a cross head 45 forming part of a spring controlled mechanism for resisting rearward sliding movement of the idler assembly on the track frame, and which mechanism is constructed as follows:

Mounted on the portion of the track frame 75 which extends between the rear sprocket wheel

4 and the front idler 12 is a housing 47 which is secured to the top flange of the channel iron 8 by a series of bolts 59 and to the top flange of the channel iron 9 by a series of bolts 60, as shown in Figs. 1 and 2. A bottom wall 56 of the housing 47 merges with upwardly converging side walls 49 and 50 as shown in Fig. 9, the side walls extending throughout the length of the housing longitudinally of the track frame, but the bottom wall 56 being of shorter length, as shown in Fig. 3, and merging at its forward end with a transverse web 61 between the side walls 49 and 50, and at its rear end with an internal flange 51 of the housing. A top opening of the housing affords access to the interior space between the web 61 and the flange 51, the top opening being normally closed by a cover 54. A vertical front wall 48 extends transversely between the side walls 49 and 50 in advance of the web 61, the latter merging with a boss 63 which extends rearwardly from the front wall 48. The boss 63 merges with a transverse top portion 52 of the housing and has a cylindrical bore 62 in it, the bore accommodating a cylindrical portion of the cross head 45 which is slidably fitted into the bore 62 for reciprocating movement longitudinally of the track frame.

The side walls 49 and 50, as indicated, continue rearwardly beyond the plane of the internal flange 51, and in rear of the flange 51 the housing 47 has a horizontally extending tubular rear portion which is interposed between and merges with the side walls 49 and 50. The upper half of the tubular rear portion forms an upwardly curved top wall 53 of the housing which connects the side walls 49 and 50, while the lower half of the tubular rear portion extends into the space between the side walls 49 and 50 in rear of the flange 51. The tubular rear portion has a circumferentially continuous inner cylindrical surface 71, and it is closed at the rear of the housing by a cover 55, bolts 81 extending through the cover and into a flange at the rear end of the housing to secure the cover 55 in place. The portions of the side walls 49 and 50 at opposite sides of the rearward tubular portion of the housing 47 have outwardly extending bottom flanges 57 and 58, respectively, as shown in Figs. 1, 2 and 9, the flange 57 having holes for the reception of the fastening bolts 59, and the flange 58 having holes for the reception of the fastening bolts 60. Similar flanges and fastening bolts are provided at the forward portion of the housing 43, as may be seen from Figs. 1 and 2.

The semi-spherical head 44 of the adjusting screw 40 bears upon a semi-spherical recess in a forward cylindrical portion of the cross head 45, said forward portion of the cross head being of smaller diameter than the socketed cylindrical portion which is fitted into the bore 62, so that the outer surface of the forward cylindrical portion of the cross head will not come in contact with the surface of the bore 62 when the cross head moves back into the housing upon track releasing movement of the idler assembly. A seal ring 64 is mounted in a circumferential groove of the portion of the cross head which slides within the bore 62, in order to prevent the ingress of foreign matter into the housing and the escape of lubricant therefrom.

The portion of the cross head 45 which slides within the bore 62 has a forwardly tapering conical recess 65 coaxial with the screw 40, and the forward end of the recess 65 is rounded to form a spherical seating surface for the ball head of a

straight link 67. The rear end of the link 67 is embraced by the forked end of an arched link 68 to which the link 67 is pivotally secured by means of a pin 69. The arched link 68 is pivotally mounted within the housing 47 by means of a pivot pin 70 which, as shown in Fig. 9, is supported in a pair of pin bosses 72 and 73 extending inwardly from the side walls 49 and 50, respectively, of the housing 47. The pin bosses 72 and 73 are located in rear of a transverse tubular bearing support 74 which is formed integrally with the housing 47, and which bearing support encloses the outer arm of a stabilizing crank 75. The inner arm of the stabilizing crank is mounted on the main body 1 of the tractor by means of a fore and aft swingable bearing 77, shown in Fig. 8, the purpose of the stabilizing crank being to retain the track frame against toeing in or out and against lateral tilting relative to the main body of the tractor in a well-known manner. For a more detailed description of the function of the stabilizing crank reference is here made to U. S. Patent 2,049,858, August 4, 1936, E. F. Norelius and W. H. Yount, Tractor frame suspension.

The tubular bearing support 74 has a stop lug 78 at its upper portion underlying the arched link 68, and another stop lug 79 is formed on the arched portion of the link 68 overlying the tubular bearing support 74, the lug 79 being adapted to engage the lug 78 for the purpose of limiting forward swinging movement of the link 68 on the pivot pin 70. Referring to Fig. 3, it will be noted that the links 67 and 68 form two arms of a toggle which reacts between the track frame and the cross head 45, and that the axis of the pivot pin 69 is slightly spaced from the dash-dotted line A—A, which represents a plane through the pivot axis of the link 68 on the track frame at 70 and through the pivot axis of the link 67 on the cross head 45. In other words, in the position of the links 67 and 68 shown in Fig. 3 the toggle occupies a moderately broken position, and the toggle is prevented from moving into its dead center position by the engagement of the lug 79 with lug 78.

Enclosed within the tubular rearward portion of the housing 47 and surrounded by the cylindrical surface 71 is a heavy coil spring 82 which has a flattened rear end abutting against the cover 55. The front end of the spring 82 is likewise flattened and bears against a spring plunger 83 which is movable back and forth on the cylindrical surface 71. The plunger 83 has a central rearwardly tapering conical recess 84, and the rear end of the recess 84 is rounded to form a spherical seating surface for the ball head of a link 85. The front end of the link 85 is embraced by a forked portion of the arched link 68 to which the link 85 is pivotally secured by means of a pin 87.

In the position of the mechanism shown in Fig. 3, which is the normal operating position of the mechanism, the coil spring 82 exerts a substantial forward pressure upon the spring plunger 83, which pressure is transmitted to the arched link 68 by the link 85 and which pressure is taken up by the tubular bearing support 74 due to engagement of the lug 79 with the lug 78. The pressure compression of the spring 82 required to produce the mentioned pressure may be obtained by screwing home the bolts 81 which retain the rear cover 55 on the housing 47, and which for that purpose are of relatively great length. The portion of the link 68 which extends between the

pivot pins 70 and 87 constitutes one arm of a second toggle whose other arm is formed by the link 85, and which second toggle reacts between the track frame and the spring plunger 83. It will further be noted that in the position of the mechanism as shown in Fig. 3 the axis of the pivot pin 87 is substantially spaced from the dash-dotted line B—B, which represents a plane through the pivot axis of the link 68 on the track frame and through the pivot axis of the link 85 on the spring plunger 83. In other words, in the position of the links 68 and 85 shown in Fig. 3 the second toggle occupies a substantially broken position.

As shown in Fig. 1, the track belt 2 is trained over the rear sprocket wheel 4 and the front idler wheel 12, both of which wheels act to support the track belt, and a series of truck rollers 88 which are mounted on the track frame bear upon the ground run of the track belt in the usual manner. The weight of the main body is sustained on the frames of the right and left track units by front and rear connections which are also of conventional construction, the track frames being pivoted on the main body coaxially with the rear sprocket wheels, and the forward portion of the main body being sustained on the track frames by means of a transverse leaf spring 89 indicated in Figs. 1 and 2. A roller 90 is mounted on the top cover 54 of the housing 47 to support the upper run of the track belt.

Figs. 1 and 2 show the front idler 12 and its bearing structure in their normal operating position, that is, in the position which the front idler 12 and its bearing structure occupy relative to the track frame and to the rear sprocket wheel 4 during normal operation of the tractor. When the tractor advances, the upper run of the track belt 2 travels in the direction of the arrow shown in Fig. 1, and the track belt must have a certain amount of slack so that its links may smoothly ride around the front idler 12 and the rear sprocket wheel 4. On the other hand, the slack of the track belt must not be excessive because the track belt would then be liable to jump off at the front idler 12 or the rear sprocket wheel 4. In the mentioned normal operating position of the front idler 12 and its bearing structure the front idler is spaced from the rear sprocket wheel 4 the correct distance which it must be spaced from said sprocket wheel in order to avoid excessive slack of the track belt and at the same time leave enough slack in it to enable the links of the track belt to ride smoothly around the front idler and the rear sprocket wheel.

It should further be noted that under normal operating conditions of the tractor the front idler 12 and its bearing structure are subject to forces which tend to move the front idler and its bearing structure longitudinally of the track frame towards the rear sprocket wheel 4, said forces resulting primarily from the weight of the upper run of the track belt 2.

Fig. 3 shows the toggle mechanisms within the housing 47 in their normal position, which normal position of the toggle mechanisms corresponds to the mentioned normal operating position of the front idler 12 and its bearing structure as shown in Figs. 1 and 2. It will be noted that in the normal position of the toggle mechanisms the arched link 68 is subject to pressure by the coil spring 82 due to the mentioned precompression of said spring, and that the position into which the link 68 is normally urged under said pressure while the front idler and its bearing

structure occupy their normal operating position is definitely and accurately determined by engagement of the stop lug 79 of the link with the stop lug 78 of the bearing support 74. In other words, the normal working position of the front idler 12 and its bearing structure is determined by the engagement of the stop lug 79 with the stop lug 78, these lugs being in engagement with each other while the front idler 12 and its bearing structure occupy the normal working position shown in Figs. 1 and 2. In the normal position of the mechanism, as shown in Fig. 3, the toggle links 67 and 68 are located fairly close to their dead center position, and, as stated hereinbefore, the coil spring 82 is pre-compressed and strongly resists movement of the toggle links 67 and 68 from their moderately broken position into a more completely broken position. Consequently, the cross head 45 will be capable of withstanding a considerable rearward thrust without starting to move in a rearward direction and the backward pressure to which the cross head 45 must be subjected in order to lift the toggle link 68 from the stop lug 78 is several times higher than the rearward pressure upon the cross head resulting from the mentioned rearward forces which normally act upon the front idler 12 and its bearing structure. The normal working position of the front idler 12 and its bearing structure may be adjusted without disturbing the normal position of the toggle mechanisms as shown in Fig. 3, by turning the adjusting screw 40.

Supposing now that a solid rock lodges itself on the lower run of the track belt in advance of the sprocket wheel 4, and that the rock is small enough to enter between the track rails 92 and to drop between two of the hinge pins 83. As the tractor advances, the clogged up portion of the track belt will come into contact with the sprocket wheel 4, and one of the teeth of the sprocket wheel will hit the rock and be prevented from entering the space which is clogged up by the rock. As a result the track tension will increase beyond normal and develop an additional back pressure upon the idler wheel 12. Such back pressure is transmitted through the idler shaft 13, the roller bearings 14, 15, brackets 18, 19, yoke 37, and screw 40 to the cross head 45, and at the cross head the back pressure will be resisted by the toggle links 67 and 68. As the clogged up portion of the track belt rides up on the sprocket wheel 4, the back pressure upon the cross head 45 increases and reaches a point where the pressure of the coil spring 82 is insufficient to keep the arched toggle link 68 against the stop lug 78. The toggle 67, 68 then starts to recede into a more completely broken position while the spring plunger 83 is forced back against the pressure of the coil spring 82 and the compression of the latter increases.

It will be noted that the toggle 67, 68 rapidly develops a mechanical advantage over the pressure of the spring 82 as the arched link 68 swings back on the pivot pin 70, and that at the same time the second toggle formed by the link 68 and the link 85 is moved from its substantially broken position towards its dead center position. The straightening movement of the second toggle produces a further mechanical advantage over the pressure of the spring 82, and as a result of the combined mechanical advantages produced by the first toggle 67, 68 and the second toggle 67, 85, the resistance opposing backward movement of the cross head 45 decreases as the cross

head 45 proceeds in a rearward or track releasing direction, although such movement of the cross head causes further compression of the spring 82 and increased pressure of the spring upon the spring plunger 83.

The two toggle mechanisms as shown in Fig. 3 are so proportional and arranged that the resistance opposing backward movement of the cross head 45 starts dropping immediately as soon as the cross head begins to move rearwardly, and that a relatively short rearward travel of the cross head which is only a small fraction of the total rearward movement of which it is capable, reduces the opposing resistance to less than half of the initial resistance which must be overcome by the cross head in order to initiate its movement in a rearward or track releasing direction. After the initial rapid decrease of the opposing resistance continued backward travel of the plunger 83 causes a further decrease of the opposing resistance, but at a slower rate than during the first small fraction of its rearward movement. Inasmuch as the resistance opposing rearward movement of the idler 12 decreases substantially during a relatively short rearward travel of the idler, all parts of the self-laying track unit, which become subject to increased stresses due to the entry of an obstruction between the track rails or otherwise, are quickly relieved from said increased stresses. The track release mechanism embodying the invention therefore reduces the danger of breakage of the stressed parts and tends to prolong the life of the self-laying track unit. After the clogged up portion of the track belt leaves the sprocket wheel 4 at the upper run of the track belt the spring 82 actuates the toggle 68, 85 and the toggle 68, 67 to move the front idler 12 and its bearing structure back into their normal working position in which they are shown in Figs. 1 and 2.

A pipe 94 abutting against the rear cover 55 of the housing 47 and extending within the coil spring 82 provides a stop for limiting backward movement of the spring plunger 83 which in turn limits the backward movement of the cross head 45 and of the front idler assembly. Fig. 4 shows the mechanism in its extreme track releasing position, and it will be noted from a comparison of Fig. 4 with Fig. 3, that in the extreme track releasing position the first toggle 67, 68 has been moved from the moderately broken position shown in Fig. 3 into a more completely broken position, while the second toggle 68, 85 has been moved from the substantially broken position shown in Fig. 3 towards its dead center position.

For purposes of identification, the arched link 68 constitutes a first link or an arm, the links 67 and 85 constitute a second link and a third link, respectively, and the cross head 45 and the spring plunger 83 constitute a first and a second reciprocable support or element, respectively.

The initial position of the toggle mechanisms, as shown in Fig. 3, is determined by engagement of the stop 79 with the stop 78, and as stated hereinbefore, the stop 78 also takes up the load of the spring 82 which is initially tensioned. As shown in Fig. 4, engagement of the plunger 83 with the tube 94 determines the final position of the toggle mechanisms and limits the deflection of the spring 82. Control of the toggle mechanisms and of the spring 82 is therefore effected by means including the tube or stop 94 which is engageable by the plunger 83, or more generally stated, by means including a stop on

the track frame, which is engageable by one of the reciprocable elements 45, 83.

The thrust transmitting yoke 37 and the adjusting screw 40 are parts of a thrust connection between the front idler 12 and the cross head 45, and they are extensibly adjustable relative to each other, namely, by rotation of the screw 40 within the threaded sleeve portion of the yoke 37 after loosening of the bolts 43. Rotation of the screw 40 is effective to adjust the front idler 12 relative to the arm 68, or more specifically stated, to adjust the axis of the front idler relative to the cross head 45, and while such adjustment is made the arm 68 may remain stationary in the limiting position thereof determined by the stop 78. Due to this arrangement, the normal position of the front idler 12 may be adjusted by means of the screw 40 without disturbing the initial position of the toggle mechanisms as shown in Fig. 3.

The links 67 and 85 have pivotal thrust connections, respectively, with the cross head 45 and with the spring plunger 83. The forwardly tapering conical recess 65 of the cross head 45 and the ball head of the link 67 constitute a socket and a thrust element, respectively, which bear upon each other in thrust transmitting direction and are freely separable from each other in the opposite direction. Similarly, the rearwardly tapering conical recess 84 of the plunger 83 and the ball head of the link 85 constitute a socket and a thrust element bearing upon each other in thrust transmitting direction and freely separable from each other in the opposite direction. The freely separable sockets and thrust elements facilitate installation of the spring and toggle mechanisms within and their removal from the housing 47.

The function of the track release mechanism 40 herein shown and described may be modified within wide limits by changing the proportions of the toggle links and their relative arrangement. For instance, it will be noted that the link 67 is connected to the arched link 68 at a longer radial distance from the axis of the pivot pin 10 than the link 85. The proportioning of these radial distances and the angular relation of the pins 69 and 81 may be selected to meet existing conditions and requirements.

It should also be noted that the entire link mechanism and the coil spring are enclosed in a compact housing 47 which is closed on all sides so that it can be filled with lubricant, the cross head 45 having a seal ring 64, as stated, to prevent the escape of lubricant through the bore 62, and the covers 54 and 55 preventing escape of lubricant at the top opening and at the rear opening of the housing. As shown in Fig. 1, an opening at the side of the housing 47 is closed by a plug 95 which may be removed in order to fill the housing 47 with lubricant to a substantial height.

While in the foregoing, a preferred embodiment of the invention has been disclosed, it should be understood that it is not intended to limit the invention to the exact details of construction herein shown and described, for various modifications within the scope of the appended claims may occur to persons skilled in the art.

70 It is claimed and desired to secure by Letters Patent:

1. In a self-laying track mechanism, a frame, a track supporting wheel and a bearing therefor movable from a normal operating position on said frame into a track releasing position, a reciproca-

ble support operatively connected with said bearing, a toggle mechanism comprising a first link pivoted on said frame, a second link pivoted on said support and a common pivotal connection between said links at such distances, respectively, from the pivot axis of said first link on said frame and from the pivot axis of said second link on said support that said toggle mechanism may occupy a moderately broken position while said bearing occupies said normal operating position, and resilient means operatively connected with said toggle mechanism to yieldingly resist movement thereof from said moderately broken position into a more completely broken position due to movement of said bearing from said normal operating position into said track releasing position.

2. In a self-laying track mechanism, a frame, a track supporting wheel and a bearing therefore movable from a normal operating position on said frame into a track releasing position, a reciprocable support operatively connected with said bearing, a toggle mechanism comprising a first link pivoted on said frame, a second link pivoted on said support and a common pivotal connection between said links at such distances, respectively, from the pivot axis of said first link on said frame and from the pivot axis of said second link on said support that said toggle mechanism may occupy a moderately broken position while said bearing occupies said normal operating position, and spring means reacting against said frame and operatively connected with said first link at a fixed radial distance from the pivot axis of said first link on said frame to yieldingly resist movement of said toggle mechanism from said moderately broken position into a more completely broken position due to movement of said bearing from said normal operating position into said track releasing position.

3. In a self-laying track mechanism a frame, a track supporting wheel and a bearing therefore movable from a normal operating position on said frame into a track releasing position, a reciprocable support operatively connected with said bearing, a toggle mechanism comprising a first link pivoted on said frame, a second link pivoted on said support and a common pivotal connection between said links at such distances, respectively, from the pivot axis of said first link on said frame and from the pivot axis of said second link on said support that said toggle mechanism may occupy a moderately broken position while said bearing occupies said normal operating position, and spring means reacting against said frame and operatively connected with said first link at a radial distance from the pivot axis of said first link on said frame, which is shorter than the radial spacing of the pivot axis of said common pivotal connection from said pivot axis of said first link on said frame; said spring means being effective to yieldingly resist movement of said toggle mechanism from said moderately broken position into a more completely broken position due to movement of said bearing from said normal operating position into said track releasing position.

4. In a self-laying track mechanism, a frame, a track supporting wheel and a bearing therefore movable from a normal operating position on said frame into a track releasing position; a reciprocable support operatively connected with said bearing; a first toggle mechanism comprising a pair of links respectively pivoted on said frame and on said support; another support reciprocably

5 mounted on said frame; a second toggle mechanism operatively connecting said first toggle mechanism with said other support; one of said toggle mechanisms being movable away from its dead center position and the other being movable towards its dead center position by movement of said bearing from said normal operating position into said track releasing position; and spring means reacting between said track frame and said other support to yieldingly resist movement of said bearing from said normal operating position into said track releasing position.

5. In a self-laying track mechanism, a frame, a track supporting wheel and a bearing therefore movable from a normal operating position on said frame into a track releasing position, a reciprocable support operatively connected with said bearing, a first toggle mechanism comprising a first link pivoted on said frame, a second link pivoted on said support and a common pivotal connection between said links at such distances, respectively, from the pivot axis of said first link on said frame and from the pivot axis of said second link on said support that said first toggle mechanism may occupy a moderately broken position while said bearing occupies said normal operating position; another reciprocable support mounted on said frame, a second toggle mechanism operatively connected with said first toggle mechanism and with said other reciprocable support, whereby movement of said first toggle mechanism from said moderately broken position into a more completely broken position, due to track releasing movement of said bearing, will move said second toggle mechanism from a substantially broken position towards its dead center position, and resilient means reacting between said frame and said other reciprocable support to yieldingly resist movement of said bearing from said normal operating position into said track releasing position.

6. In a self-laying track mechanism, a frame, a track supporting wheel and a bearing therefore movable from a normal operating position on said frame into a track releasing position, a first reciprocable support operatively connected with said bearing, a first toggle mechanism comprising a first link pivoted on said frame, a second link pivoted on said first support and a common pivotal connection between said first and second links at such distances, respectively, from the pivot axis of said first link on said frame and from the pivot axis of said second link on said first support that said first toggle mechanism may occupy a moderately broken position while said bearing occupies said normal operating position; a second reciprocable support mounted on said frame, a second toggle mechanism comprising a third link pivoted on said second support and a pivotal connection between said first and third links at such distances, respectively, from the pivot axis of said first link on said frame and from the pivot axis of said third link on said second support that said second toggle mechanism may occupy a substantially broken position while said first toggle mechanism occupies said moderately broken position; and resilient means reacting between said frame and said second support to yieldingly resist movement of said second toggle mechanism from said substantially broken position towards its dead center position due to movement of said first toggle mechanism from said moderately broken position into a more completely broken position by movement of said bearing from its normal op-

erating position into said track releasing position.

7. In a self-laying track mechanism, a frame, a track supporting wheel and a bearing therefor movable from a normal operating position on said frame into a track releasing position, a first link mounted on said frame for pivotal movement relative thereto about a first axis, a second link pivotally connected with said first link on a second axis spaced from said first axis, means including a reciprocable support operatively connected with said bearing and pivotally connected with said second link on a third axis spaced from said second axis, whereby said third axis in the position thereof corresponding to said normal operating position of said bearing will be spaced from said first axis so as to locate said second axis in relatively close proximity to a plane through said first and third axes, at one side thereof, and whereby movement of said bearing from said normal operating position into said track releasing position will cause said second axis to recede from said plane at said one side thereof, means for preventing approach of said second axis towards said plane, at said one side thereof, beyond said position of relatively close proximity thereto, and pressure means operatively connected with said links to resiliently resist said receding movement of said second axis from said plane.

8. In a self-laying track mechanism, a frame, a track supporting wheel and a bearing therefor movable from a normal operating position on said frame into a track releasing position, a first link mounted on said frame for pivotal movement relative thereto about a first axis, a second link pivotally connected with said first link on a second axis spaced from said first axis, means including a reciprocable support operatively connected with said bearing and pivotally connected with said second link on a third axis spaced from said second axis, whereby said third axis in the position thereof corresponding to said normal operating position of said bearing will be spaced from said first axis so as to locate said second axis in relatively close proximity to a plane through said first and third axes, at one side thereof, and whereby movement of said bearing from said normal operating position into said track releasing position will cause said second axis to recede from said plane at said one side thereof, and spring means reacting against said frame and operatively connected with said first link to resiliently resist said receding movement of said second axis, said first link having a portion engageable with a stop on said track frame to prevent approach of said second axis towards said plane, at said one side thereof, beyond said position of relatively close proximity of said second axis to said plane.

9. In a self-laying track mechanism, a frame extending in the direction of propulsion of the mechanism, a track supporting wheel and a bearing therefor mounted at one end of said frame for movement longitudinally thereof, a spring abutment mounted on said frame in spaced relation to said bearing, a coil spring seated at one end on said abutment and extending longitudinally of said frame towards said bearing, a plunger engaged by the other end of said coil spring, a first link pivoted on said frame in the space between said spring abutment and said bearing, a cross head mounted on said frame for movement longitudinally thereof in the space between the pivot axis of said first link and said bearing,

a second link connecting said first link with said cross head, a third link connecting said first link with said plunger, and a thrust transmitting connection between said cross head and said bearing.

10. In a self-laying track mechanism, a frame extending in the direction of propulsion of the mechanism, a track supporting wheel and a bearing therefor mounted at one end of said frame for movement longitudinally thereof, a spring abutment mounted on said frame in spaced relation to said bearing, a coil spring seated at one end on said abutment and extending longitudinally of said frame towards said bearing, a plunger engaged by the other end of said coil spring, a first link pivoted on said frame in the space between said spring abutment and said bearing, a cross head mounted on said frame for movement longitudinally thereof in the space between the pivot axis of said first link and said bearing, a second link connecting said first link with said cross head, a third link connecting said first link with said plunger, relatively stationary and movable stop elements associated, respectively, with said frame and with said first link and engageable with each other to limit movement of said first link by movement of said plunger, said coil spring being compressed to urge said movable stop element into engagement with said stationary stop element, and an extensible thrust transmitting connection between said cross head and said bearing.

11. In a self-laying track mechanism, a frame extending in the direction of propulsion of the mechanism, a track supporting wheel and a bearing therefor mounted at one end of said frame for movement longitudinally thereof, a spring abutment mounted on said frame in spaced relation to said bearing, a coil spring seated at one end on said abutment and extending longitudinally of said frame towards said bearing, a plunger engaged by the other end of said coil spring, a first link pivoted on said frame in the space between said spring abutment and said bearing, a cross head mounted on said frame for movement longitudinally thereof in the space between the pivot axis of said first link and said bearing, a second link connecting said first link with said cross head, a third link connecting said first link with said plunger, a thrust transmitting connection between said cross head and said bearing, and relatively stationary and movable stop elements associated, respectively, with said frame and with said plunger to limit movement of said plunger towards said abutment.

12. In a self-laying track mechanism, a frame extending in the direction of propulsion of the mechanism, a track supporting wheel and a bearing therefor mounted at one end of said frame for movement longitudinally thereof, a spring abutment mounted on said frame in spaced relation to said bearing, a coil spring seated at one end on said abutment and extending longitudinally of said frame towards said bearing, a plunger engaged by the other end of said coil spring, a first link mounted on said frame for pivotal movement about a first axis in the space between said spring abutment and said bearing, a cross head mounted on said frame for movement longitudinally thereof in the space between said first axis and said bearing, a second link pivoted on said cross head and connected with said first link for pivotal movement about a second axis spaced from said first axis, a third link pivoted on said plunger and connected with

said first link for pivotal movement about an axis spaced from said first axis a shorter distance than said second axis, and a thrust transmitting connection between said cross head and said bearing.

13. In a self-laying track mechanism, the combination with a track frame, and a track supporting idler wheel having a bearing supported on said frame for movement longitudinally thereof in a track releasing direction, of means for controlling said movement of said bearing comprising a spring controlled toggle mechanism operatively connected to said bearing to resist said movement thereof and having three pivot points, a first supported in fixed position on said frame, a second movable longitudinally of said frame, and a third movable transversely of said frame.

14. In a self-laying track mechanism, the combination with a track frame, and a track supporting idler wheel having a bearing supported on said frame for movement longitudinally thereof in a track releasing direction, of means for controlling said movement of said bearing comprising a spring controlled toggle mechanism having three pivot points, a first supported in fixed position on said frame, a second movable longitudinally of said frame, and a third positioned intermediate the said first and second points and movable transversely of said frame, and thrust transmitting means operatively connecting said second pivot point to said bearing.

15. In a self-laying track mechanism, the combination with a track frame, and a track supporting idler wheel having a bearing supported on said frame for movement longitudinally thereof in a track releasing direction, of means for controlling said movement of said bearing comprising a spring controlled toggle mechanism having three pivot points, a first supported in fixed position on said frame, a second movable longitudinally of said frame, and a third positioned intermediate the said first and second points and movable transversely of said frame, and a pair of thrust transmitting elements respectively connected to said bearing and to said toggle mechanism at said second pivot point of the latter, the said thrust transmitting elements being adjustably connected to each other to permit adjustment of the axis of said idler wheel relative to the said second pivot point.

16. In a self-laying track mechanism, the combination with a track frame, and a track supporting idler wheel having a bearing supported on said frame for movement in a track releasing direction, of means for controlling said movement of said bearing comprising a spring controlled toggle mechanism operatively connected to said bearing to resist said movement thereof and having five pivot points, a first supported in fixed position on said frame, a second movable longitudinally of said frame, a third positioned intermediate said first and second points and movable transversely of said frame, a fourth movable longitudinally of said frame, and a fifth positioned intermediate the said first and fourth points and movable transversely of said frame.

17. In a self-laying track mechanism, a track frame, a track supporting wheel movable longitudinally of said frame in track tensioning and track releasing directions, an arm pivoted on said frame, connecting means between said wheel and arm operable to swing said arm in one direction by said track releasing movement

of said wheel and to move said wheel in said track tensioning direction by swinging movement of said arm in the opposite direction, a resilient element, and connecting means between said

5 resilient element and said arm operable to tension said resilient element by said swinging movement of said arm in said one direction and to swing said arm in the opposite direction by the reaction of said resilient element, one of 10 said connecting means comprising an element guided on said frame for reciprocating movement relative thereto in a direction transversely of the pivot axis of said arm, and a link connection between said reciprocable element and said arm operable to develop a progressively increasing 15 mechanical advantage during said track releasing movement of said wheel, effective to reduce the resistance of said resilient element against said track releasing movement of said wheel.

20 18. In a self-laying track mechanism, a track frame, a track supporting wheel movable longitudinally of said frame in track tensioning and track releasing directions, an arm pivoted on said frame, connecting means between said wheel and arm operable to swing said arm in one direction by said track releasing movement of said wheel and to move said wheel in said track tensioning direction by swinging movement of said arm in the opposite direction, a resilient 25 element, and connecting means between said resilient element and said arm operable to tension said resilient element by said swinging movement of said arm in said one direction and to swing said arm in the opposite direction by the reaction of said resilient element, each of said connecting means comprising an element guided on said frame for reciprocating movement relative thereto in a direction transversely of the 30 pivot axis of said arm, and a link connection between said reciprocable element and said arm operable to develop a progressively increasing mechanical advantage during said track releasing movement of said wheel, effective to reduce the resistance of said resilient element against said track releasing movement of said wheel.

35 19. In a self-laying track mechanism, a track frame, a track supporting wheel movable longitudinally of said frame in track tensioning and track releasing directions, an arm pivoted on said frame, a resilient element, connecting means between said resilient element and said arm operable to tension said resilient element by swinging movement of said arm in one direction and to swing said arm in the opposite direction by the reaction of said resilient element, an element guided on said frame for reciprocating movement relative thereto transversely of the pivot axis of said arm, connecting means between said wheel and said reciprocable element operable to move the latter in one direction by said track releasing movement of said wheel, and to move said wheel in said track tensioning direction by movement of said reciprocable element in its opposite direction, and a link having relatively spaced pivot centers on said reciprocable element and on said arm, respectively, and cooperating with the latter to develop a progressively increasing mechanical advantage during said track releasing movement of said wheel, effective to reduce the resistance of said resilient element against said track releasing movement of said wheel.

40 20. In a self-laying track mechanism, a track frame, a track supporting wheel movable longi-

tudinally of said frame in track tensioning and track releasing directions, an arm pivoted on said frame, connecting means between said wheel and arm operable to swing said arm in one direction by said track releasing movement of said wheel and to move said wheel in said track tensioning direction by swinging movement of said arm in the opposite direction, a resilient element, an element guided on said frame for movement relative thereto in opposite directions transversely of the pivot axis of said arm and cooperating with said resilient element to tension the latter by movement in one of said directions, and a link having relatively spaced pivot centers on said movable element and on said arm, respectively, and cooperating with the latter to develop a progressively increasing mechanical advantage during said track releasing movement of said wheel, effective to reduce the resistance of said resilient element against said track releasing movement of said wheel.

21. In a self-laying track mechanism, a track frame, a track supporting wheel movable longitudinally of said frame in a track releasing direction, a resilient element, and a mechanism connecting said wheel with said resilient element operable to develop a progressively increasing mechanical advantage during said track releasing movement of said wheel, effective to reduce the resistance of said resilient element against said track releasing movement of said wheel, said mechanism comprising a pivoted arm, means connecting said arm with said resilient element for tensioning the latter by swinging movement of said arm in one direction, a stop for limiting swinging movement of said arm in the opposite direction, and connecting means between said wheel and arm including a pair of relatively adjustable elements operable to adjust said wheel relative to said arm while the latter remains stationary in the limiting position thereof determined by said stop.

22. In a self-laying track mechanism, a track frame, a track supporting wheel movable longitudinally of said frame in a track releasing direction, a resilient element, and a mechanism connecting said wheel with said resilient element operable to develop a progressively increasing mechanical advantage during said track releasing movement of said wheel, effective to reduce the resistance of said resilient element against said track releasing movement of said wheel, said mechanism comprising an arm pivoted on said frame, means connecting said arm with said resilient element for tensioning the latter by swinging movement of said arm in one direction, a stop on said frame engageable by said arm for limiting swinging movement of said arm in the opposite direction, and connecting means between said wheel and arm including a pair of relatively adjustable elements operable to adjust said wheel relative to said arm while the latter remains stationary in the limiting position thereof determined by said stop.

23. In a self-laying track mechanism, a track frame, a track supporting wheel movable longitudinally of said frame in a track releasing direction, a resilient element, and a mechanism connecting said wheel with said resilient element operable to develop a progressively increasing mechanical advantage during said track releasing movement of said wheel, effective to reduce the resistance of said resilient element against said track releasing movement of said wheel, said mechanism comprising an arm pivoted on said

frame, means connecting said arm with said resilient element for tensioning the latter by swinging movement of said arm in one direction, a stop on said frame for limiting swinging movement of said arm in the opposite direction, an element guided on said frame for reciprocating movement relative thereto, a link having relatively spaced pivot centers on said arm and reciprocable element, respectively, and a pair of relatively adjustable elements cooperating, respectively, with said wheel and with said reciprocable element operable to adjust said wheel relative to the latter.

24. A self-laying track mechanism comprising, a track frame, a track supporting wheel movable on said frame in a track releasing direction, a first reciprocable element guided on said frame and having a thrust connection with said wheel for transmitting track releasing movement of said wheel to said first reciprocable element, an arm pivoted on said frame, a link pivoted on said arm and having a pivotal thrust connection with said first reciprocable element for transmitting track releasing movement of said wheel to said arm, a second reciprocable element guided on said frame, another link pivoted on said arm and having a pivotal thrust connection with said second reciprocable element for transmitting track releasing movement of said wheel to said second reciprocable element, and resilient means cooperating with said second reciprocable element to yieldingly resist said track releasing movement of said wheel.

25. A self-laying track mechanism as defined in claim 24, in which at least one of said pivotal thrust connections comprises a socket and a thrust element bearing upon each other in thrust transmitting direction, said socket and thrust element being freely separable from each other in the opposite direction.

26. A self-laying track mechanism comprising, a track frame, a track supporting wheel movable on said track frame in a track releasing direction, a first reciprocable element guided on said frame and having a thrust connection with said wheel for transmitting track releasing movement of said wheel to said first reciprocable element, a second reciprocable element guided on said frame, toggle mechanism for transmitting track releasing movement of said wheel from said first to said second reciprocable element, comprising an arm pivoted on said frame, a link pivoted on said arm and having a thrust connection with said first reciprocable element, another link pivoted on said arm and having a thrust connection with said second reciprocable element; resilient means cooperating with said second reciprocable element to yieldingly resist track releasing movement of said wheel; and control means for said toggle mechanism and said resilient means, including a stop on said frame engageable by one of said reciprocable elements.

27. A self-laying track mechanism as defined in claim 26, in which the control means for said toggle mechanism and said resilient means includes a stop on said frame engageable by said second reciprocable element.

28. A self-laying track mechanism as defined in claim 26, in which said thrust connection between said first reciprocable element and said wheel comprises a pair of thrust transmitting elements extensibly adjustable relative to each other.
